UNITED STATES PATENT OFFICE.

ALFRED BRAKE AND ROBERT JAMES MCKEE, OF WELLINGTON, NEW ZEALAND; SAID MCKEE ASSIGNOR TO SAID BRAKE.

AERATED-WATER FOUNTAIN OR ENGINE.

SPECIFICATION forming part of Letters Patent No. 606,373, dated June 28, 1898.

Application filed October 28, 1897. Serial No. 656,656. (No model.) Patented in New Zealand May 27, 1897, No. 9,569; in New South Wales June 5, 1897, No. 7,522, and in England August 6, 1897, No. 18,362.

To all whom it may concern:

Be it known that we, ALFRED BRAKE and ROBERT JAMES MCKEE, subjects of the Queen of Great Britain, and residents of 54 Lambton Quay, Wellington, in the Colony of New Zealand, have invented certain new and useful Improvements in Aerated-Water Fountains or Engines, of which the following is a specification.

10 The invention has been patented in New Zealand, No. 9,569, dated May 27, 1897; in New South Wales, No. 7,522, dated June 5, 1897, and in Great Britain, No. 18,362, dated August 6, 1897.

15 This invention relates to fountains or engines used for drawing off aerated water; and its object is to provide a fountain whereby aerated water may be drawn from bulk and delivered into a glass tumbler or other receptacle in such a manner that it will retain a highly effervescing and sparkling condition and whereby aerated waters of various kinds may be drawn off or mixed by one operation.

20 It is well known to mineral-water manufacturers that when aerated waters are drawn from bulk immediately into a tumbler the effervescence is comparatively slight and soon passes off, leaving the liquid "flat." To avoid this drawback, it has been the custom 25 to draw off the waters into bottles, whence the liquid is poured into a glass.

The present invention provides means for overcoming the necessity of bottling aerated water.

30 Means are provided for registering the number of glasses of aerated water which are served by the apparatus.

In carrying out the invention a column is fixed upon the counter or other suitable support, and a pipe passing up this column connects an ordinary cylinder or receiver containing aerated water to a chamber branching out of the column. The chamber has an arrangement of valves operated by a lever, 35 whereby the top and bottom of the said chamber may be closed while aerated water under pressure is admitted, the supply of water cut off, the gas allowed to escape at the top, and then the water drawn off at the bottom after 40 the pressure has been removed. By the same

movement of the lever one of a number of syrup-pumps is operated and the aerated water flavored as desired. The admission of aerated water and gas to the chamber operates a recorder to register the number of 55 glasses drawn off.

In order that the invention may be most easily understood by a skilled person, reference will be made to the accompanying drawings while giving a description in detail. 60

Figure 1 is a side view of the apparatus, partly in section and the hand-lever curtailed. Fig. 2 is a plan of the same. Fig. 3 is a front view of a grid or guide. Fig. 4 is a part section showing a modification of the chamber. 65 Fig. 5 is a cross-section of the chamber on line A B, Fig. 1.

Similar reference-letters indicate corresponding parts throughout the views.

Making reference to the drawings, the column *a* is fixed to a counter or other support by means of its flange *a'* and covers a pipe *a''*, which connects any ordinary cylinder or receiver placed below the counter and containing aerated water in bulk under pressure to 70 the chamber *b*. A hand-lever *c*, fulcrumed at *c'*, may be operated to depress spindle *b'* against the resilience of spring *b''*. In descending the spindle will force downward the india-rubber washer *b³* by means of its collar 75 *b⁴* and close the aperture *b⁵* in the division-plate *b¹⁵*. The collar *b⁶* will now be pressing upon the bell-crank lever *b⁷* and the rubber valve *b⁸* upon its seat at the bottom of the chamber. The lever continuing to descend, 80 the rubber washer *b³* will be compressed, valve *b⁹* opened, and spindle *b* pass down upon the stem *b¹⁰* of valve *b⁸*, the pin *b¹¹*, fixed in spindle *b*, sliding in slot *b¹²* of stem *b¹⁰* and allowing this movement. Aerated water will 85 enter through the apertures *b¹³* and *b¹⁴* and hollow valve *b⁹* into the chamber *b*, when the pressure of the gas will operate the recorder *p*. The lever *c* may be made to descend within the central aperture *d'* of grid *d*, Fig. 90 95 3, when aerated or soda water will be drawn from the receiver in a pure state, or it may first be moved laterally to descend within any of apertures *d²*, *d³*, *d⁴*, or *d⁵*, when one of spindles *c²*, *c³*, *c⁴*, or *c⁵*, connected to any ordinary 100

syrup-pump below the counter, will be raised by one of tappets b^2 , b^3 , b^4 , or b^5 and syrup forced through one of nozzles f^2 , f^3 , f^4 , or f^5 into a glass placed ready to receive the same.

- 5 The hand-lever is now raised, when valve b^9 will close and compression of washer b^8 be removed. The chamber b will now contain a given quantity of aerated water and gas, and the raising of the lever being continued 10 the gas will snift through aperture b^5 into the upper part of chamber b and thence through orifice b^{20} into the atmosphere or into a pipe which may be provided, if desired, to carry off the gas. The lever is then still further raised until pin b^{11} engages with the top 15 of slot b^{12} to raise the valve b^8 until the parts assume the positions shown on Fig. 1 and allow the aerated or soda water to flow through apertures b^{16} and nozzle b^{17} . The water is thus 20 first relieved of pressure and in such condition is mixed with the flavoring-syrup, already referred to as having been pumped into the glass. The cycle of operations is here given step by step, but the whole action is so rapid 25 that there is no hesitation and the flow of the syrup and soda-water is practically simultaneous.

The rubber washer b^8 is inclosed in a metal washer b^{21} in order that it may be forced down 30 upon the plate b^{15} with sufficient force to prevent escape of gas at high pressures.

The valve b^9 is made water-tight upon its seat by means of a sleeve b^{22} , of india-rubber or the like, which is slipped upon and shaped 35 to fit the nozzle b^{23} .

By employing four syrup-pumps, as shown, it is possible to have as many flavoring-syrups. Thus, soda-water, ginger-ale, lemonade, ginger-beer, and pine-apple flavor may be obtained 40 from the same fountain and in rapid succession by a mere lateral movement of the lever to cause it to descend within any of the apertures in grid d . The column c^1 , to which lever c is fulcrumed, is fitted revolubly within bracket c^8 and guide c^9 to provide for the movement of the lever to the right or left.

Fig. 4 shows a modification of chamber b , where the same is extended to form a mixing-chamber h . The nozzles f^2 , f^3 , f^4 , and f^5 50 enter into this mixing-chamber, and the flavoring-syrup and soda-water flow out of the one nozzle b^{18} into the glass. The shield h' prevents the soda-water rising within the nozzles.

55 The nozzles f^2 , f^3 , f^4 , and f^5 have kinks f^6 to prevent an excess of drip, as it is found that the thick syrups will cling to the nozzles, and thus the various flavors become undesirably mixed unless precautions are taken to 60 obviate the same. The kinks are formed as near the mouth of the nozzles as convenient, in order to have as short a length of piping to be drained as possible. It will be seen that the portion to be drained is from the apex of 65 the kink to the mouth, and to assist the rapidity of the draining small holes j are provided to admit air. The direction of holes is as

shown in the section Fig. 1—that is, in the same direction as the flow of the syrup and so that there may be little tendency for the 70 syrup to rise into and escape through the hole. The curtailing of the drip is further assisted by the diaphragms k' in the hollow globes k , so that when any one of spindles c^2 , c^3 , c^4 , or c^5 is lifted one of the diaphragms is raised and air 75 drawn into the globe through the nozzle; but when the spindle falls and the greater part of the syrup has flowed back from the nozzle into the pump-column c^{18} a puff of air is forced through the nozzle to clear the same of syrup 80 dripping from the mouth of the nozzle.

To operate the recorder p , the gas is conducted through a pipe p' into the head of the column c^{18} or other convenient support. The recorder may be any well-known form of 85 multiplying-gear, and, as shown on the drawings, a ratchet-wheel p^2 has one hundred teeth on its periphery and a pin p^3 on its face which engages once every revolution with a wheel having ten teeth to change the figure p^4 and record the hundreds. Similarly pins on wheels of figures p^4 and p^5 operate similar wheels of ten teeth to change figures p^5 and p^6 in a well-known manner. The ratchet-wheel p^2 is operated by a pawl p^7 , which is kept to its work 95 by the gravity of weight p^8 or by a spring and is jointed to the lever p^9 . This said lever is fulcrumed at p^{10} and has an adjusting-screw p^{11} resting upon a friction-plate p^{12} , attached to diaphragm p^{13} . Thus when the chamber b 100 is filled the gas lifts the diaphragm by passing along pipe p' , the diaphragm raises the lever and pawl, and the ratchet-wheel is revolved through the space of one tooth, pins p^{14} regulating the lift of lever p^9 . The recorder is secured to the column or otherwise 105 closed, so that it cannot be tampered with.

Throughout the description we have shown the recorder p as operated by the expansion of the gas in the chamber b before it is released therefrom; but it is obvious that the pipe p' may be connected to the orifice b^{20} and the snift of the gas used to operate the recorder.

We prefer to make the parts which come 115 into contact with the liquids of aluminium, as this metal is admirably adapted to our purpose since it has little tendency to corrode.

We wish it to be understood that we have specified herein such constructions and materials as we consider preferable, but that we do not confine ourselves to such details, as these may be modified in several ways without exceeding the ambit of the invention, and throughout this specification the apparatus 120 has been described as being used for drawing off soda-water; but it is obvious that it may be used for other aerated drinks, such as 125 aerated beer.

What we claim, and desire to secure by Letters Patent of the United States, is—

1. The improved fountain for aerated waters under pressure, comprising the measuring-chamber, the pipe connection between

said chamber and a suitable receiver, the valve normally closing said communication, the normally open valve controlling the outlet from said chamber, means for simultaneously operating said valves, an automatic gas-operated recorder and mechanism carried by said pipe connection and connected with the recorder, said mechanism being operated by the sudden rise in pressure inside the chamber, substantially as described.

2. A fountain or engine for drawing off aerated waters from bulk consisting of a suitably-supported chamber provided with a spindle carrying a washer to close an opening at

15 the top and a valve to close the bottom of the chamber and a collar, a bell-crank lever adapted to be engaged by said collar, an admission-valve operated by said bell-crank and a lever to operate such spindle whereby all the operations are performed by one movement, substantially as and for the purposes set forth herein.

3. A fountain or engine for drawing off aerated waters from bulk consisting of a suitably-supported chamber provided with a spindle carrying a washer to close an opening at

25 the top and a valve to close the bottom of the chamber and a collar, a bell-crank lever adapted to be engaged by said collar, an admission-valve operated by said bell-crank, a pipe connection connecting said chamber with a receiver, a recorder, mechanism connected with

30 the recorder and operated by the sudden rise in pressure inside the chamber and a lever to operate the spindle whereby all the operations are performed by one movement, substantially as and for the purposes set forth herein.

4. A fountain or engine for drawing off aerated waters from bulk consisting of a suitably-supported chamber provided with a spindle carrying a washer to close an opening in

40 the top and a valve to close the bottom of the chamber and a collar, a bell-crank lever adapted to be engaged by said collar to open an admission-valve, pumps for delivering flavoring-syrups, a lever having a bearing-piece adapted to operate said spindle and having tappets and a grid to operate said pumps and whereby all the operations may be performed by one move-

45 ment, substantially as and for the purposes set forth herein.

5. A fountain for drawing aerated waters from bulk comprising a chamber, a spindle

movable therein and carrying a washer to close an opening at the top of chamber and a valve 55 to close an opening at the bottom of the chamber, a pipe connection from said chamber to a receiver, a bell-crank operating a valve for controlling said pipe connection, a collar on the spindle, a recorder, and mechanism connected with said recorder and operated by the sudden rise in pressure in the chamber, pumps for delivering flavoring-syrups, a rocking lever adapted to operate said spindle, tappets carried by the pump piston-rods adapted to 60 be engaged by said lever and a grid, substantially as described.

6. In a fountain adapted to deliver aerated water from a storage-receptacle containing it under gas-pressure, the combination with the 70 measuring and delivering chamber having a pipe connection with such storage-receptacle, of a recorder, a diaphragm connected with said chamber and adapted to be moved by the pressure of the gas on each operation of 75 the fountain, and a pawl-and-ratchet connection between said diaphragm and recorder, substantially as described.

7. In an aerated-water fountain, the combination with the water-delivery apparatus of 80 the syrup-delivery pipes, the delivery-nozzles therefrom having kinked ends with an air-hole in the apex of said kink, and means for sending a puff of air through said nozzle, substantially as described.

8. A fountain or engine for drawing off aerated waters from bulk consisting of a suitably-supported chamber provided with a spindle carrying a washer to close an opening in the top and a valve to close the bottom of the 90 chamber and a collar, a bell-crank lever adapted to be engaged by said collar, an admission-valve operated by said bell-crank, pumps for delivering flavoring-syrups into a mixing-chamber, a lever adapted to operate said 95 pumps and spindle and whereby all the operations may be performed by one movement, and a grid, substantially as and for the purposes set forth herein.

In witness whereof we have hereunto set 100 our hands this 29th day of September, 1897.

ALFRED BRAKE.

ROBERT JAMES MCKEE.
